UNITED STATES PATENT OFFICE.

JOHN M. GIBLIN, OF SHEBOYGAN, WISCONSIN.

DESIGN FOR A BOTTLE OR SIMILAR VESSEL.

SPECIFICATION forming part of Design No. 15,910, dated March 3, 1885.

Application filed December 24, 1884. Term of patent 7 years.

To all whom it may concern:

Be it known that I, JOHN M. GIBLIN, a citizen of the United States, residing at Sheboygan, in the county of Sheboygan and State of Wisconsin, have invented and produced a new and original Design for Bottles or Similar Vessels, of which the following is a specification, reference being had therein to the accompanying drawings, in which—

- 10 Figure 1 is a side elevation, and Fig. 2 a bottom view.
My design is represented in the accompanying drawings; and it consists in the external configuration or shape of the vessel.
15 A is the top, and below this is the straight neck B, extending from the point *a* to the point *b*, and of somewhat less diameter than that of the top. From *b* to *b'* the base of the neck swells out, forming the part B', and from 20 *b'* to *c'* the vessel is substantially conical, which forms the part C, and then below this the vessel rounds out and down from *c'* to *c*, forming the part C', while from *c* to *d* the

sides are substantially vertical, forming the body proper, D, while from *d* to *e* the vessel 25 rounds down in the line of an ellipse, forming the part E, and terminating in the flat central bottom wing, *e*, or base proper, *e'*. Within this ring the base is slightly recessed, as best shown in the bottom view, Fig. 2, while 30 the side elevation, Fig. 1, best illustrates the general appearance of the vessel.

Having thus described and illustrated my new and original design, I claim—

The design for a bottle or similar vessel, 35 consisting of the top A, straight neck portion B, swelled neck-base B', conical part C, swelled part C', vertical-sided part D, rounded base part E, and central bottom ring, *e'*, as shown and described. 40

In testimony whereof I affix my signature in presence of two witnesses.

JOHN M. GIBLIN.
